UNITED STATES PATENT OFFICE.

GEORGE L. RICE, OF CHICAGO, ILLINOIS, ASSIGNOR TO INTERNATIONAL HARVESTER COMPANY OF NEW JERSEY, A CORPORATION OF NEW JERSEY.

SPINNING-MACHINE.

1,217,067.

Specification of Letters Patent. Patented Feb. 20, 1917.

Continuation of application Serial No. 844,783, filed June 12, 1914. Abandoned May 31, 1916. This application filed May 27, 1916. Serial No. 100,288.

To all whom it may concern:

Be it known that I, GEORGE L. RICE, a citizen of the United States, residing at Chicago, in the county of Cook and State of Illinois, have invented certain new and useful Improvements in Spinning-Machines, of which the following is a full, clear, and exact specification.

This invention relates to spinning machines.

Heretofore in the manufacture of twine two systems have been employed. One of these systems makes use of the roving gill spinner, which has been used for the spinning of soft and short fibers for commercial yarn. The other system makes use of the ordinary spinning jenny, which is in general use for spinning hard, coarse fibers into a single strand yarn, such as binder twine. By means of the first system an even twine is spun, but it is left in a rough, unfinished condition. By means of the other system a glossy finish is given to the twine, but the twine is not evenly spun. Thus far no spinning machine has been made which is capable of producing a firm, even twine throughout its length, and at the same time giving such twine a smooth finish.

It, therefore, is the main object of my invention to produce twine which, when spun, is even throughout its length, and at the same time has a smooth, hard, glossy finish.

Another object is to provide a spinning machine having coöperating members for producing twine adapted to meet all of the commercial requirements.

These objects are accomplished by providing in a spinning machine the combination of a nipper, means for positively feeding to the nipper a sliver of fiber of the proper size to produce twine of the desired tensile strength, and means for pulling the sliver through the nipper and twisting it into twine after it passes through the nipper.

This invention is illustrated on the accompanying sheets of drawings, in which—

Figure 1 is a fragmentary side elevation,

parts being in section, of a spinning machine embodying my invention;

Fig. 2 is a fragmentary plan view of the same spinning machine;

Fig. 3 is a side elevation of the machine, parts being shown in section, and showing more in detail the driving connections for the various parts of the machine; and

Fig. 4 is a fragmentary sectional view of coöperating parts of my improved spinning machine for producing twine having the desired qualities mentioned.

The various novel features of my invention will be apparent from the description and drawings and will be particularly pointed out in the appended claims.

This spinning machine includes a main frame 10, upon which is rotatably mounted the usual flier head 11, to which the capstan or haul pulleys 12 are connected, the bobbin 13 being mounted in the usual manner. Secured to another portion 14 of the frame is a support 15 forming the lower half of split bearings 16 and 17, the upper half of the split bearings being formed in a cap 18 secured to the lower half by bolts 19. Rotatably mounted in the bearings 16 and 17 are shafts 20 and 21, upon which are mounted rollers 22 and 23, preferably having scratched or grooved surfaces running longitudinally thereof for reasons to be considered later. These rollers 22 and 23 are actuated from any suitable source including a driving shaft 25, having associated therewith a change speed gearing including a plurality of graduated gears 26 adapted to be engaged by a sliding gear 27 mounted on and keyed to a shaft 28, to which is operatively connected a suitably supported sprocket wheel 29. A chain 30 passes around this sprocket wheel and drives another sprocket wheel 31 mounted upon a shaft 32. Upon one end of the shaft 32 is a bevel gear 33 meshing with a bevel gear 34 mounted upon one end of shaft 21. It is seen, therefore, that the shaft 21 receives its motion through a system of transmitting members from shaft 25. The rotary movement trans-

mitted to shaft 21 causes the roller 23 to be rotated. Also mounted on shaft 21 is a gear 21^a which meshes with a gear 35 mounted upon a stub shaft 36. Gear 35 in turn meshes with a gear 20^a secured to the shaft 20. The gears 21^a, 35 and 20^a being of the same diameter, said rollers 22 and 23 are driven at the same speed.

Coöperating with and engaging both of the rollers 22 and 23 is a relatively large roller 37, preferably having a leather or other good frictional surface 38. This roller 37 is mounted upon a shaft 39 rotatable in bearing blocks 40, which are slidably mounted in enlarged coöoperating portions 41 of a pair of arms 42 pivoted to upright supporting members 43 by means of trunnions 44. The arms 42 have portions 43^a which are pivotally connected to a pair of links 45, respectively, which in turn are pivotally connected to a pair of arms 46 loosely mounted upon a shaft 47 mounted in the upper ends of the support 43. These arms 46 have projections 48 which are connected by a bridging member 49. Also loosely mounted upon the shaft 47 is a member 50, having a projection 51, through which passes an adjustable screw 52 which engages the bridging member 49. This member 50 has a hook portion 53 which is connected by a link 54 to one end of a spring or resilient member 55, the other end of which spring is connected to a hook 56 secured to a stationary portion of the machine. This spring 55, through the various connecting members, yieldingly presses the roller 37 into contact with the smaller rollers 22 and 23. The pressure between the roller 37 and rollers 22 and 23 may be regulated by the adjusting screw 52. By means of the bearing blocks 40 of the rollers 37 being slidably mounted in the arms 42, the roller 37 may assume its proper position relative to the rollers 22 and 23.

Also mounted upon the frame of this machine is a nipper consisting of a pair of separable nipper dies 58, at the receiving end of which is a conical guide 57. The upper nipper die is pressed toward the lower nipper die by means of its own weight, which is increased by a weighted portion 59. Also suitably supported adjacent the delivery side of the nipper is a pair of separable smoothing dies 60, the upper die portion 61 being held against the lower by a weighted member 62, being pivotally mounted at 63 and bearing upon a fork member 64, which is secured to the upper portion 61 of this pair of smoothing dies.

Adjacent the rollers 22 and 37 is a drawing chain 66, having the usual needles 67, the chains being actuated by a sprocket wheel 68 mounted upon a shaft 69, upon which is mounted a gear 70, which meshes

with a pinion 71 adjustably mounted in a 65 pivotally mounted bracket 72. Rotating with the pinion 71 is a larger gear 73, which is in mesh with a pinion 74 mounted upon one end of shaft 21. By means of the transmission connections between the shafts 21 and 69, including the reducing gears, the chain 66 is given a relatively slow movement.

Secured to a suitable support 80 is a bar 81, upon which is pivotally mounted at 82 a 75 bar 83, the downward movement of which is limited by a projection 81^a on the bar 81. Resting against the bar 83 is the upper end of a guiding conductor 84, having sides 85 and a top 86 forming guiding portions for 80 guiding the fiber passing from the chain 66 and directly between the drawing rollers 22, 23 and 37. The side portions 85 of the guiding conductor 84 are provided with arcuate portions 85^a which rest and ride 85 upon smooth portions of the roller 22. The upper end of the conductor may be adjusted by a screw 83^a passing through the bar 83. In passing from the chain 66 the strands of fiber are properly guided, by means of a 90 conductor 84, between the rollers 22 and 37, so that none of the fiber will be deflected from the proper direction of movement. There is a distinct advantage in having the two rollers 22 and 23 to coöperate with the roller 37 instead of having just one. This advantage consists in maintaining contact of at least one of the smaller rollers 22 and 23 with the roller 37 at all times. For instance, if the fiber which is drawn between the 100 rollers 22 and 37 is sufficient to force the roller 37 an appreciable amount out of engagement with the roller 22, there will still be contact between the rollers 23 and 37, in this way insuring a proper drawing action 105 from the chain 66 and the proper feeding from the roller 23 to the nipper 58. The same is true with respect to rollers 22 and 37 if the rollers 23 and 37 are separated. By means of the movable bearing blocks 40, 110 in which the shaft of roller 37 is mounted, the roller 37 may be moved to assume a position in accordance with proper operating conditions.

In spinning machines heretofore used the 115 amount of fiber drawn from the chain into the nipper and smoothing dies was entirely controlled by the tension device or capstan pulleys, and the uniformity of twine depended very largely on the ease with which 120 the different fibers entered the nipper, there being nothing positive in the way of a uniform feed at that point. With such an arrangement it is readily apparent that the fiber drawn from the chain may vary in 125 amount to a considerable extent. Any foreign substance might easily clog the nipper and cause a temporary interruption to the

passage of the fiber. With such a method of producing twine, the twine naturally is rendered more or less uneven, although presenting a comparatively smooth and hard surface after passing through the smoothing die. To overcome this undesirable unevenness of twine, I have provided intermediate the nipper and chain 66 a system of co-operating drawing rollers 22, 23 and 37, which travel at a surface speed several times higher than the material is fed toward them by the chain 66, the sliver thus being positively drawn from the chain, reduced and positively fed as an untwisted sliver of the proper size or volume to the nipper. The primary function, therefore, of these drawing rollers is to control the evenness of the twine by positively drawing the fiber from the chain, reducing it to the proper size to produce twine of a desired tensile strength, and positively feeding it as a sliver to the nipper in a manner such that the evenness of the twine throughout its entire length is greatly improved. The nipper pinches the sliver in order that such sliver may be twisted into twine by the action of the flier, and the nipper also prevents the twist from extending back to the drawing rollers. At this point it is to be noted that the flier head 11 is driven from the power shaft 25, which is the same source of power from which the drawing rollers and the chain 66 are driven. In other words, there is a definite relationship between the speed of the flier head 11 which places the twist in the twine, the capstan pulleys 12, which are carried by the flier head, and the drawing rollers which positively draw the sliver from the chain 66 and positively feed it to the nipper 58. In order to produce this desirable twine, the capstan pulleys 12 must positively pull the sliver through the nipper and the twine away from the nipper at the same rate of speed as the sliver is fed to the nipper. It, therefore, is important that the driving relationship, or speed relationship, of the various parts in question should be definitely determined. To insure the proper relative drawing of the fiber from the chain 66, feeding it to the nipper, and the proper pulling of the sliver through the nipper by the capstan pulleys 12 as it is twisted into twine by the flier head 11, there is provided a change speed gear intermediate the drive shaft 25 and chain 30 for making the desired fine adjustments whereby delicate speed control is obtained.

In this twine spinning machine, therefore, there is provided a source of fiber supply, a nipper, drawing rollers for drawing fiber from the source of supply and reducing it to the proper size sliver to produce a twine of the proper tensile strength and for feeding the fiber positively to the nipper, mech-

anism including means such as the capstan 65 pulleys and flier head for pulling the sliver through the nipper and twisting it to form twine, means for adjusting the relative speeds of the parts in question, and smoothing dies on the delivery side of the nipper 70 for smoothing and polishing the twine as it is being twisted.

By means of this machine, therefore, it is possible to produce a twine which not only presents a smooth, hard, glossy finish, but 75 also twine which is more even throughout its entire length than heretofore has been the case.

There may be various modifications in my invention other than here particularly 80 shown and described, and it is my intention to cover all such modifications which do not involve a departure from the spirit and scope of my invention as set forth in the following claims.

What I claim as new is:

1. In a twine spinning machine, the combination of a nipper, means for positively feeding to said nipper a sliver of the proper size to produce twine of the desired tensile 90 strength, means for pulling said sliver through the nipper and twisting it into twine after it passes through the nipper, and smoothing dies on the delivery side of the nipper for smoothing and polishing the 95 twine as it is being twisted.

2. In a twine spinning machine, the combination of a source of fiber supply, a nipper, means for drawing fiber from said source of supply and reducing it to the 100 proper size sliver to produce twine of the desired tensile strength and for feeding the sliver positively to the nipper, and means for pulling the sliver through the nipper and twisting it to form twine.

3. In a twine spinning machine, the combination of a nipper, means for positively feeding to said nipper at a definite rate of speed a sliver of proper size to produce twine of the desired tensile strength, and 110 means for pulling the sliver through the nipper at substantially the same rate of speed as it is fed to the nipper and twisting it to form twine after it passes through the nipper.

4. In a twine spinning machine, the combination of a nipper, means for positively feeding to said nipper at a definite rate of speed a sliver of proper size to produce twine of the desired tensile strength, means 120 for pulling the sliver through the nipper at substantially the same rate of speed as it is fed to the nipper and twisting it to form twine after it passes through the nipper, and means for adjusting the relative speed of said feeding and pulling means.

5. In a twine spinning machine, the combination of a nipper, means for positively

41
feeding to said nipper a sliver of fiber of the proper size to produce twine of a desired tensile strength, and means for pulling the sliver through the nipper and twisting it 5 into twine after it passes through the nipper.

6. In a twine spinning machine, the combination of a source of fiber supply, a nipper, means for drawing the fiber from the 10 source of supply, reducing it to the proper

size sliver to produce a twine of desired tensile strength and for positively feeding the sliver to the nipper at a definite rate of speed, and means for pulling the sliver through the nipper at substantially the same 15 rate of speed as it is fed thereto and twisting it to form twine.

In testimony whereof I affix my signature.

GEORGE L. RICE.
